(57) **CLAIM**

The ornamental design for a syringe head cap for liquid dispensing machine, as shown and described.

DESCRIPTION

FIG. 1 is a front view thereof, showing a syringe head cap for liquid dispensing machine of my new design;

FIG. 2 is a back view thereof;

FIG. 3 is a right side view thereof;

FIG. 4 is a top plan view thereof;

FIG. 5 is a cross-sectional view taken from the cut line 5-5 in FIG. 1;

FIG. 6 is a perspective view thereof; and,

FIG. 7 is a view of a syringe head cap for liquid dispensing machine shown in a position of use.

The broken lines in the drawings depict environment that forms no part of the claimed design.

1 Claim, 7 Drawing Sheets
